UNITED STATES PATENT OFFICE.

JOHN W. H. DOUBLER, OF ROCKFORD, ILLINOIS, ASSIGNOR TO HIMSELF
AND MOSES E. HAIGHT, OF SAME PLACE.

ALBUM.

SPECIFICATION forming part of Letters Patent No. 228,451, dated June 8, 1880.

Application filed March 16, 1880. (No model.)

To all whom it may concern:

Be it known that I, JOHN W. H. DOUBLER, of the city of Rockford, in the county of Winnebago and State of Illinois, have invented a new and useful Picture-Album, of which the following is a specification.

My invention relates to that class of albums employed mainly as a receptacle of photographs, but is adapted to receive pictures or other like articles as a convenient method of preserving them and arranging them for reference; and it consists in providing a case of book-like form, in two parts, hinged to open freely, and supporting in the case leaf-like receptacles on suitable hinged connections to fold and unfold freely in the case. These and other improvements, all of which will be hereinafter more fully described, constitute the subject-matter of this specification.

In the accompanying drawings, Figure 1 is an isometrical representation of my improved album opened with the casings at right angles. Fig. 2 is an isometrical representation of the album closed. Fig. 3 is a sectional view of the hinged edge portion of the album on a transverse line at the upper edge of the hinged connection, and Fig. 4 is a transverse section of one of the leaf-like portions at its hinged connection with the case.

The outer case of my improved album is in its main outline of book form, in two box-like parts, in which *a* represents the board-like portions, which, in this instance, are fitted with an outside border, *b*, made in any suitable plain or ornamental form, and its edge portions *c* rise from the boards and meet in the center, forming recessed box-sides of a depth sufficient to receive the leaf-like portions inside of the box.

The leaf-like receptacles are of suitable outline form and size to freely enter and be received in the box, and are composed of three thicknesses, the centerply or portions of which, as at *d*, are placed at the outer vertical edges, the vertical central divisions, and at the bottom; and the sides are suitably formed in open panels *e*, the openings of which are of a less width than the openings between the vertical center plies. These parts, consisting of the center and side plies, are firmly glued, cemented, or otherwise fixed together, producing

leaf-like plates having open panels, and provided with edge grooves or channels *f*, open at the upper end, through which to insert the pictures, to be passed in the edge grooves into position to expose the pictures in the open panels. These leaves, including the casing, may be made from wood, finished or covered with leather fabrics, paper, or any suitable material, plain or ornamental; or each individual piece may in itself be made from different kinds of materials in any variety of finish or style applicable to such work, and the several parts may vary in the materials of which they are formed and in their finish. The two parts of the casing and the several leaves are all hinged to swing freely on the same lengthwise center *h*, parallel to the lengthwise central joint in the back of the case.

In this method of hinging the several parts the leaves of the hinge with which the case is connected are of substantially the same form, placed with their like faces opposite each other. This is also true of the leaf-hinges of each pair of leaves taken in pairs from the opposite halves in their successive order, one from each side, commencing with the outside leaves and taken toward the centers, or commencing at the center and taken outward toward the casing; but in each such respective pairs of the hinge-leaves the angle portion of the leaves varies to a sufficient extent to permit the several leaves to fold freely into the case and onto each other, all of which is clearly represented in the drawings, but especially in section in Fig. 3, in which the pairs are designated by like letters of reference, in which *i* represents the leaves of the hinge which connects the casings, *k* represents the hinge-leaves on which the outside pair of album-leaves are hinged, and *l* the hinge-leaves on which the inner pair of album-leaves are hinged, from which it will be readily seen that, in order to have the several pairs of leaves fold snugly into the case and on each other properly, it is necessary that each pair of hinged leaves are formed with the proper angles to adapt them to the particular position for which they are designed.

At *m* is represented a bracket, designed to be fixed in a vertical position in any conven-

ient place by means of suitable screws, which may be passed through the holes *n* in its end portions. This bracket is fitted with hooking-arms *o*, which project from its front side at proper points. These hook-arms are designed to engage suitable eyes fixed in position to the case, in or at its back-center joint, in the same lengthwise line of the hinges of the case.

5 The object of this part of my invention is to 10 suitably suspend my improved album in a convenient manner for reference, and from which position it may be readily removed and as readily replaced when required.

15 By this method of constructing albums I am enabled to produce albums in great varieties and styles from a great variety of materials not heretofore employed in the manufacture of such goods, and I am also enabled to produce an album of greater durability, and to 20 better preserve its contents, and to produce a new article of manufacture.

I claim as my invention—

25 1. In an album, the combination, with a two-part case, said parts being hinged together and adapted to have their inclosing sides meet in edge-bearing, of a series of album-leaves hinged in line with the hinge-joint of the case, substantially as set forth.

30 2. In an album, the combination, with a two-part case hinged together, of a series of album-leaves adapted to be inclosed within the case and hinged on a common center, the outer al-

bum-leaves on both sides being provided with angular hinges respectively inclining in opposite directions from the central portion of 35 the album, substantially as set forth.

3. In an album, the combination, with a two-part case, said parts being hinged together and adapted to have their inclosing sides meet in edge-bearing, of a series of album-leaves 40 hinged on a common center in line with the hinge-joint of the case, the outer album-leaves being provided with angular hinges, substantially as set forth.

4. In an album, the combination, with a two-part case, the parts of which are hinged together and adapted to have their inclosing sides meet in edge-bearing, of a series of album-leaves 45 hinged on a common center in line with the hinge-joint of the case, the outer album-leaves being provided with angular hinges, substantially as set forth.

5. In an album, the combination, with a two-part case, said parts being hinged together and adapted to have their inclosing sides meet in edge-bearing, and a series of album-leaves 55 hinged on a common center in line with the hinge-joint of the case, of a bracket provided with arms which engage with the back of the case in line with its hinge-joint, substantially as set forth.

JOHN W. H. DOUBLER.
